M. JACKSON.

DIRIGIBLE HEADLIGHT FOR AUTOMÓBILES.

APPLICATION FILED NOV. 25, 1919.

1,381,124.

Patented June 14, 1921.

UNITED STATES PATENT OFFICE.

MAXEY JACKSON, OF EMMETT, IDAHO.

DIRIGIBLE HEADLIGHT FOR AUTOMOBILES.

1,381,124.

Specification of Letters Patent. Patented June 14, 1921.

Application filed November 25, 1919. Serial No. 340,527.

To all whom it may concern:

Be it known that I, MAXEY JACKSON, a citizen of the United States, residing at Emmett, in the county of Gem and State of Idaho, have invented certain new and useful Improvements in Dirigible Headlights for Automobiles, of which the following is a specification.

This invention relates to certain new and useful improvements in dirigible headlights for automobiles, and it has for its objects among others to provide simple and efficient means whereby the headlight may be readily operated by the steering rod.

Other objects and advantages of the invention will hereinafter appear and the novel features thereof will be particularly pointed out in the appended claim.

The invention is clearly illustrated in the accompanying drawing which, with the numerals of reference marked thereon, form a part of this specification, and in which—

Figure 1 is a perspective view of my improvement.

Fig. 2 is a detail view of the operative connections on a larger scale.

Fig. 3 is an enlarged vertical view of the lamp and the member connected with the pivot thereof.

Like numerals of reference indicate like parts throughout the different views.

Referring to the drawings,

1 designates the steering rod of an automobile, of the usual type, adapted for steering the car in the usual way. 2 is a housing, through the top and bottom walls of which the said rod or post 1 passes, and fast on this rod within the housing is a bevel gear 3. The housing may be supported on the rod 1 in any suitable manner, and extended through a side wall thereof is a shaft 4 carrying within the housing a bevel gear 5 meshing with the bevel gear 3. The shaft 4 has a bearing in the support 6 adjacent the housing, as seen in Figs. 1 and 2, and at its other end carries the upwardly extended lugs 7—7, each having a vertical slot 8 closed at their upper and lower ends, and in these slots work freely the lateral

50 pins or the like 9, which extend from opposite sides of the operating bar 10.

11 are the lamps carried by the forks 12 attached to some fixed part of the automobile and holding the outer casings of the lamps in fixed position.

13 is the reflector of the lamp, pivotally mounted at top and bottom, as at 14 and 15, the pivot 15 at the bottom being extended downward and beyond the casing 16 of the lamp, as seen in Fig. 3, and this extended end is connected by means of the arm 17 with the operating rod 10, as seen in Figs. 1 and 3. The other end of the rod 10 is likewise connected to the bottom pivot of the reflector of the other lamp, as seen in Fig. 1, so that as the rod 10 is actuated the two reflectors will be simultaneously turned on their pivots.

18 is a socket for a bulb 19, suitable wiring being designed to be provided, as usual.

In operation, as the steering post is turned to steer the automobile, the rod 10 is actuated and through the connections above described the reflectors are turned upon their pivots in unison by means of the arms 17.

While primarily designed, and as herein shown, my improvement is applied to an automobile, I would call attention to the fact that my present improvement is applicable to other uses, such as other forms of vehicles, and other bodies without departing from the spirit of the invention or sacrificing any of its advantages.

What is claimed as new is—

In a dirigible headlight, a casing, a reflector pivotally mounted with relation thereto, an operating arm connected with one of the pivots of said reflector, an operating bar connected to said arm, a steering rod, a shaft operatively connected therewith, and a loose connection between said shaft and rod, said loose connection embodying slotted lugs rising from said shaft and lateral members on the bar loosely engaged in the slots of the lugs.

In testimony whereof I hereunto affix my signature in the presence of two witnesses.

MAXEY JACKSON.

Witnesses:

V. T. CRAIG,

J. L. STEWARD.
